(57) **CLAIM**

The ornamental design for a recording medium container, as shown and described.

DESCRIPTION

The article to which the design is to be applied is a container for a recording medium, such as a CD, DVD and MD, which comprises two lids capable of being opened to right and left, wherein: each of the lids has a projected holder for easily holding the medium in the cavity provided in each of the lids at the central hole of the medium and removing the medium under conditions wherein the lids are opened, together with a projection in the form of an arc for protecting the outer edge of the medium; and one of the lids has a pamphlet holder.

FIG. 1 is a front elevation view of a recording medium container showing the new design, in a closed condition;

FIG. 2 is a rear elevation view thereof;

FIG. 3 is a top view thereof;

FIG. 4 is a right side view thereof;

FIG. 5 is a left side view thereof;

FIG. 6 is a front, left side perspective view thereof;

FIG. 7 is a front elevation view thereof, in an opened condition and drawn on a reduced scale;

FIG. 8 is a right side view thereof, in an opened condition and drawn on a reduced scale;

FIG. 9 is a cross-sectional view thereof, taken along line 9-9 in FIG. 7;

FIG. 10 is an enlarged portion of a top plan view thereof, taken along line 10-10 in FIG. 7;

FIG. 11 is a cross-section view thereof, taken along line 11-11 in FIG. 10;

FIG. 12 is a cross-section view thereof, taken along line 12-12 in FIG. 10; and,

FIG. 13 is a front, right side perspective view thereof, in an opened condition drawn on a reduced scale.
